UNITED STATES PATENT OFFICE.

ALEXANDER MARSH AND SIDNEY A. ANDERSON, OF FLEMINGTON, MISSOURI.

COAL CARRIER FOR TENDERS.

Application filed May 13, 1926. Serial No. 108,877.

This invention relates to coal carriers for locomotive tenders and has for its object to produce means whereby the fireman can always maintain the pile of coal close to the front end of the tender and not have to spend a good deal of his time walking back and forth the length of the tender in order to obtain coal for feeding the locomotive, and also to obviate the employment of an extra hand or coal passer to shovel the coal to the front end of the tender.

With the general objects named in view and others as may hereinafter appear, we have produced a strong, efficient, durable and inexpensive construction; and in order that it may be fully understood, reference is to be had to the accompanying drawings, in which:—

Figure 1 is a side view of the rear end of a locomotive and tender equipped with apparatus embodying the invention.

Figure 2 is a top plan view of the same, with the locomotive cab omitted.

Figure 3 is a section on the line III—III of Figure 1.

Figure 4 is a side view of the tender, partially broken away to disclose parts otherwise hidden.

Figure 5 is an enlarged top plan view of the locomotive drivers with apparatus forming the power mechanism.

Figure 6 is an enlarged view of the control mechanism for clutching and unclutching the device.

In the said drawings, where like reference characters identify corresponding parts in all of the figures, 1 indicates the locomotive cab and 2 the locomotive tender.

The coal carrier comprises a relatively L-shaped scoop comprising a bottom member 3, a rear wall 4 and side walls 5, the side walls being braced by inclined braces 6, said carrier being of sufficient width to extend from side to side of the tender.

The rear bottom corners of the carrier are preferably formed with upstanding housing portions 7 within which are journaled rollers or wheels 8 on a transverse shaft 9, the front edge of said carrier scraping or sliding over the bottom of the tender. It will be understood that in normal position when the tender is to be loaded with coal, the carrier will stand at the rear end of the tender and against the back wall

thereof. The coal is then loaded as customary.

As the engine is fired and the coal is gradually shoveled by the fireman away from the front end of the tender, the fireman turns a control wheel 10 fixed to the end of an inclined rod 11 journaled in a bearing 12 carried by the floor of the tender. The other end of the rod extends below the floor of the locomotive cab and is equipped with a universal joint 13 connected to a shaft 14 journaled in a bearing 15 depending from the floor of the locomotive cab 1.

The end of the short shaft 14 carries a disk 16 from the face of which projects a pair of pins 17. Rotatively secured to the pins 17 and normally standing in the position shown in Figure 6, are a pair of curved links 18, it being evident that the parts as shown in said figure have passed center and the device is locked against accidental operation.

The ends of the links 18 are each pivotally secured to pins 19 carried by straps 20 loosely encircling a driving axle 21 of the locomotive. The straps 20 are each fitted between a pair of plates 22 and the ends of a pair of cable reels 23 freely mounted on the axle 21. Secured to substantially the center of the engine axle 21 is a fixed abutment member 24 and between the opposite sides of said member and the plates 22 are a pair of expansion springs 25.

The outer ends of plates 26 of each of the cable reels 23 are formed with a notch 23^a, and fixedly secured to the engine axle are a pair of pins 27 for driving engagement with the notches 23^a. It will be evident that the fireman by rotating the operating rod 11 can release the cable reels so that notches 23^a shall engage the pins 27 and power shall be applied to rotate the cable reels, the springs assisting the fireman in sliding the cable reels longitudinally of the axle 21. It will be understood that this is done only when the engine is travelling at a low rate of speed.

Coiled around each of the reels 23 are cables 28 which lead rearwardly and upwardly over guide pulleys 29 and are secured at their ends to the front corners of the coal carrier. It will be apparent from the mechanism described, that the fireman can effect the forward movement of the coal

carrier and thus maintain the coal in close proximity to the fire box. It will be apparent that the front end of the carrier by scraping on the floor of the tender will positively effect the movement of all of the coal forwardly, and that as the greater part of the weight of the coal will be carried by the rollers 8 no undue strain will be placed on the cables or operative mechanism.

10 In order to return the carrier to normal position, a transverse shaft 30 is journaled in bearings 31 at the rear end of the tender, and mounted on the ends of said shaft are a pair of gear wheels 32 enmeshed with chains 33 extending forwardly and upwardly and encircling a pair of gear wheels 34 mounted on stub shafts 35 carried by the side walls of the tender and equipped with crank handles 36 for operation.

20 The transverse shaft 30 carries a pair of cable reels 37 on which suitable cables 38 are wound, the ends of said cables being secured to the rear corners of the coal carrier. It will be evident that rotation of the 25 crank handles 36 in the proper direction will effect the rearward movement of the coal carrier, the cables 38 unwinding from the reels 37 to accommodate this backward or return movement of the coal carrier.

25 From the above description, it will be apparent that we have produced a device possessing the features of advantage set forth as desirable, and while we have described and claimed the preferred embodiment of 35 the same, it is to be understood that we re-

serve the right to make all changes properly falling within the spirit and scope of the appended claims.

We claim:

1. The combination in a locomotive tender 40 of a coal carrier longitudinally movable of said tender, a reel, a driven axle, clutch connections between said reel and axle for effecting operation of the former, and a flexible connection between said reel and coal carrier, and means for returning said carrier to initial position.

2. The combination in a locomotive tender 45 of a coal carrier longitudinally movable of said tender, a driven axle, a pair of reels on said axle and each forming one member of a pair of clutches, a second pair of clutch members on said axle, connections between said reels and coal carrier, and means to effect simultaneous opposite movement of said 50 reels to engage the clutch members.

3. The combination in a locomotive tender 55 of a relatively L-shaped scoop adapted to move longitudinally upon the bottom of the tender and having its front edge in contact with said tender bottom, a pair of wheels supporting the rear portion of said scoop, a reel, a flexible connection between said reel and scoop, a driven axle, and clutch connections for engaging said reel and driven axle 60 for the operation of the former.

In witness whereof, we hereunto affix our signatures.

ALEXANDER MARSH.
SIDNEY A. ANDERSON.
